UNITED STATES PATENT OFFICE.

EZRA W. CARTER, OF COHOES, NEW YORK.

DESIGN FOR A DRAIN OR OTHER PIPE.

SPECIFICATION forming part of Design No. 19,677, dated March 4, 1890.

Application filed February 3, 1890. Serial No. 339,077. Term of patent 14 years.

To all whom it may concern:

Be it known that I, EZRA W. CARTER, a citizen of the United States, residing at Cohoes, in the county of Albany and State of New York, have invented and produced a new and original Design for Drain or other Pipes, of which the following is a specification.

My design relates to drain and other pipes; and the leading feature thereof consists in a cylindrical section of a pipe or tube having upon its extremities semicircular or substantially semicircular collars or strips, partly overlapping upon the exterior surface of the pipe-section and in part extending beyond the end of such pipe-section, both of said collars or strips being arranged in coincident planes or upon the same side of the pipe-section.

To more fully disclose said design I will make reference to the accompanying drawing, in which the figure is a perspective view of my design.

In the said drawing, the reference-numeral 1 denotes a section of pipe of cylindrical form, 25 or substantially so, and of any preferred length. Lapped upon each end of the tubular section and arranged in coincident planes are semicircular or substantially semicircular collars or strips 2, applied directly to the 30 exterior surface of the pipe, one portion of

each projecting beyond the end of the pipe-section, while the other and remaining portion is lapped upon the half-circumference of said pipe-section. By the arrangement of these collars in coincident planes I intend that it shall be understood that both are applied to the same side of the pipe-section, having relation to a plane passing longitudinally through the axis of the pipe, in contradistinction to applying one semicircular 35 collar upon one side of such a plane and the other upon the other side thereof at the other end of the pipe-section.

What I claim as my design is—

The design for a section of pipe herein 45 shown and described, the same consisting of a tubular section provided at its ends with substantially semicircular collars, partly lapped on the exterior of such tubular section and partly projecting beyond the ends thereof, 50 said collars being arranged upon the same side of the pipe-section or in coincident planes, substantially as described.

In testimony whereof I affix my signature in presence of two witnesses.

EZRA W. CARTER.
